UNITED STATES PATENT OFFICE.

ALEXANDER McNAUGHTON, OF BUFFALO, NEW YORK.

PROCESS OF MOLDING.

1,218,437.

Specification of Letters Patent.

Patented Mar. 6, 1917.

Application filed August 23, 1916. Serial No. 116,443.

To all whom it may concern:

Be it known that I, ALEXANDER McNAUGHTON, a citizen of the Dominion of Canada, residing at Buffalo, county of Erie, and 5 State of New York, have invented certain new and useful Improvements in a Process of Molding, of which the following is a full, clear, and exact description.

It is well known to those skilled in the 10 art, that when molding large castings it is necessary that the cope be removed before the casting is cold in order that the usual shrinking may take place without restriction. Before the cope is removed it is necessary that the sand be broken away around 15 the risers provided in the mold. The sand around the risers, as is well known, must be supported by gagers and these are placed very close to the print when the pattern is 20 molded. When the mold is poured the metal coming up through the riser causes the sand around the riser to fuse with the ends of the gagers. When the casting is still red hot the sand must be broken away from around 25 the risers before the cope can be removed and because of the fusing above mentioned this operation is extremely difficult, in view of the excessive heat. This necessitates much extra labor and requires considerable 30 time. In producing my invention I have sought to provide a process in which the above objections may be overcome. My invention comprises a process wherein means are employed for holding the sand to shape 35 around the risers and thus permitting the gagers to be set back far enough so that they will not fuse with the sand around the risers when the mold is cast.

In the accompanying drawings I have 40 shown one form of means or apparatus for carrying out my process, but it is obvious that other means or apparatus of different form may be employed with equal efficiency. In the drawings:

45 Figure 1 represents a fragmentary, plan view of a mold provided with apparatus for carrying out my process, the sand in this view, for clearness of illustration, being omitted.

50 Fig. 2 is a sectional elevation of the apparatus taken on line 2—2 of Fig. 1.

Fig. 3 is a perspective view of one of the 55 filler casings employed in carrying out my process.

Fig. 4 is a perspective view of the key used for withdrawing the filler casings.

Fig. 5 is a fragmentary, plan view of the apparatus, showing sand between the filler casings.

Referring now to the drawings, and more 60 particularly to Figs. 1 to 3 inclusive, 5 represents a molding flask of which 6 is the cope and 7 the drag or molding floor. 8 are the usual flask bars which support the gagers 9.

65 In Fig. 2, 10 represents the pattern within the mold and 11 the riser print, these parts, for clearness of illustration, having been omitted in Fig. 1. 12 is the well known pad core which is placed upon the pattern and 70 beneath the print 11 and which is removed and replaced by the usual core when the pattern is withdrawn.

75 13 is a filler which preferably comprises a plurality of filler casings 14. Each of these filler casings is preferably hollow and provided with tapering walls whereby each casing is larger at its top side than at its bottom. In the top face of each casing is provided an elongated slot 17, whereby the 80 casing may be lifted by means of the key 16 shown in Fig. 4. These filler casings are so designed that when placed together the filler has a slightly larger diameter than the diameter of the riser print. This provides 85 space for a sand lining 15. The filler casings 14 may be placed close together (as shown in the drawings) or they may be separated slightly so as to permit the sand to be passed therebetween, which facilitates some- 90 what their easy withdrawal.

95 When the apparatus shown in the drawings is to be used the pattern 10 is placed within the drag of the flask or on the molding floor and the cope 6 placed over the same. The pad core 12 is placed upon the pattern where each of the risers is to come and upon this core is placed the riser print 11. About this riser print are now placed the filler casings 14. The gagers 9 are now 100 put into position with their ends closely adjacent to the filler casings 14 and the mold is rammed up in the usual manner.

105 After the casting is poured and has become sufficiently solid to remove the cope, the key 16 is placed within the slot 17 of each of the filler casings and the same withdrawn from the sand. This leaves a space between the sand surrounding the riser and the sand about the filler, so that the cope 110 may be easily removed.

It will be clearly seen from the foregoing

that with my process the risers and the cope may be quickly and easily removed without the disagreeable labor which attends the old method of releasing.

Having thus described my invention, what I claim is:

1. The herein described process, comprising the placing of a filler about the riser print of a pattern, then placing the gagers in position with their ends adjacent to the filler, and then ramming sand between the filler and the print and into the mold.
- 10 2. The herein described process, comprising the placing of a filler, larger than the

riser print, around about said print, then placing the gagers in position with their ends adjacent to the filler, and then ramming sand between the filler and the print and into the mold.

In testimony whereof, I have hereunto signed my name in the presence of two subscribing witnesses.

ALEXANDER McNAUGHTON.

Witnesses:

J. WM. ELLIS,
WALTER H. KELLEY.
